UNITED STATES PATENT OFFICE.

OLIVER C. JONES, OF PHILADELPHIA, PENNSYLVANIA.

ROTARY PUMP.

SPECIFICATION forming part of Letters Patent No. 712,937, dated November 4, 1902.

Application filed March 8, 1902, Serial No. 97,252. (No model.)

To all whom it may concern:

Be it known that I, OLIVER CROMWELL JONES, of the United States Navy, a citizen of the United States, and a resident of Philadelphia, in the county of Philadelphia and State of Pennsylvania, have invented a new and Improved Rotary Pump, of which the following is a full, clear, and exact description.

10 This invention relates to a rotary pump constructed to be easily reversed, and adapted particularly to be used in connection with my improved rotary engine, application for Letters Patent for which is filed of even date 15 herewith, although, if desired, power of any form may be employed to drive the pump.

This specification is an exact description of one form of my invention, while the claims define the actual scope thereof.

20 Reference is to be had to the accompanying drawings, forming a part of this specification, in which similar characters of reference indicate corresponding parts in all the views.

Figure 1 is a horizontal section of the invention on the line 1 1 of Fig. 3. Fig. 2 is a section on the line 2 2 of Fig. 3. Fig. 3 is an elevational view from the line 3 3 of Fig. 2, and Fig. 4 is a cross-section on the line 4 4 of Fig. 2.

30 Referring to Fig. 1, 10 indicates the pump-cylinder, and 11 the engine-cylinder. The engine-cylinder is fitted with a rotary piston 12, abutments 15, and steam-controlling devices 16, all as described in my copending application above referred to. As Fig. 1 illustrates, the engine and pump are coupled directly together, the cylinders being divided by a wall 17. This arrangement of the rotary engine and pump is according to my preference; but obviously an engine of any sort might be used to drive the pump.

As best shown in Figs. 3 and 4, the pump-cylinder 10 has offset portions 18 at each side, and in these pairs of offsets pairs of abutments 19 are arranged to work. These abutments 19 are carried on trunnion-shafts 20, which are mounted in the sides of the cylinder.

21 indicates the pump-piston, which has a packing-strip 22 at its outer end, this packing-strip being pressed outward by a spring 23, so as to make water-tight connection with the pump-cylinder and with the abutments.

The piston is arranged to turn in the cylinder and coacts with the abutments, as will be fully described hereinafter, the abutments 55 rocking on their trunnion-shafts to allow the piston to pass them and afterward falling back upon the piston and its hub 24, as the drawings show.

25 indicates the inlet-pipe, which passes 60 into the cylinder 10, preferably at the bottom, and 26 indicates the outlet or discharge pipe, which passes from the center thereof. Mounted in the cylinder at the side of the piston is a transverse wall 27, which has circular edges engaging the sides of the cylinder. This wall 27 is cut away at two points, (indicated at 28 and 29,) such points lying adjacent to and on opposite sides of the piston, as best shown in Fig. 4. The opening 28 does 70 not extend to the periphery of the wall and is therefore an inclosed opening, and the opening 29 extends outward to the periphery of the wall, as Fig. 4 shows. This wall 27 is fastened rigidly to or formed integral with 75 the hub 24 of the piston, so as to turn therewith. This fastening may be effected in any desired manner; but it is preferred to cast or otherwise form integral the parts 21, 24, and 27. Formed on the right-hand side of the 80 wall (see Fig. 2) is a casing 30, which communicates with the said opening 28 in the wall, this casing 30 lying between the wall and the right-hand head of the cylinder and having a centrally-disposed opening 31 in exact registry with the discharge-pipe 26.

35 32 indicates packing of any suitable form placed at the end of the outlet 30, so as to prevent leakage at this point, and 33 indicates packing extending around the periphery 90 of the wall 27 from one side of the opening 19 to the other.

The hub 24 has at its left-hand or inner end a central extension 34, which is set in a bearing 35, formed in the central wall 17, 95 and this extension 34 has mortised engagement with a corresponding extension 36 from the hub of the engine-piston. This connects the two pistons rigidly together, so that the latter may be turned from the former. 37 100 indicates a tie-rod which is passed through the hub of the piston 21 and the extension 34 and screwed into the hub of the engine-piston 21. At the right-hand end of the rod 37

a nut 38 is placed, and this nut presses a spring 39 against the wall 27, whereby the parts 21, 27, 30, and 12 are drawn forcibly against the central wall 17, so as to prevent leakage. The engine - piston is carefully packed, as illustrated and described in my before-referred-to copending application, and the pump-piston 21 may also be packed as desired, so as to keep it water-tight. The abutments 15 of the engine are actuated by steam-pressure, so as to yieldingly maintain their proper positions, and the pump-abutments 19 are connected with the engine-abutments, so that the pump-abutments also will be held yieldingly in the proper position. This connection is effected by tenoning together the trunnion-shafts 20 of the pump-abutments with the trunnion-shafts 40 of the piston-abutments, as indicated at 41. The construction is given greater strength by means of studs 42, fastened to or formed integral with caps 43, which are held on the outer head of the engine-cylinder and project into the hollow trunnion-shafts 40. The trunnion-shafts 20 are also hollow and have placed therein cylindrical blocks 44, which are fastened rigidly to rods 45. These rods 45 project through the adjacent ends of the trunnion-shafts 20 and 40 and are screwed into the studs 42. These parts 42, 45, and 44 being rigid and carrying loosely the trunnion-shafts allow the abutments to swing freely, but at the same time they sustain them firmly in the proper adjustment, and even should the left-hand head of the pump-cylinder be removed the pump-abutments will not fall from place.

The operation of the pump is as follows: As the steam-pressure is applied to the engine-abutments it is transmitted to the pump-abutments by the abutment-connecting devices, and when the steam is admitted into the engine-cylinder the pump-piston is driven around in the pump-cylinder. The movement of the piston carries with it the wall 27 and case 30, and the liquid is sucked in through the pipe 25, it passing into the space between the wall 27 and the adjacent head of the pump-cylinder. The water is drawn from here by the sucking action of the pump through the opening 29 in the wall 27 and lies in the cylinder back of the piston, assuming that the piston be moving in the direction of the arrow indicated in Fig. 4. Simultaneously the water is being forced out through the opening 28, case 30, and discharge 31. Assuming the parts to be in the position shown in Fig. 4, the piston moving to the left will coat with the lower left-hand abutment 19, and the water will thus be forced through the opening 28. As the movement of the piston continues this discharge action will be continued until the piston strikes the lower left-hand abutment and passes the same, whereupon the piston in moving around toward the right-hand side acts with the upper right-hand abutment 19

in the same manner as that above described. Meanwhile the sucking action of the pump goes on continuously, thus keeping the cylinder at all times full of the water ready for the action of the piston in forcing it out through the discharge. The pump may be readily reversed, so as to drive it in either direction and so as to convert the discharge 26 into the inlet and the inlet 25 into the discharge. The reversal of the engine of course is necessary to the reversal of the pump, and, as may be understood by reference to my copending application, the reversal of the engine will also reverse the steam-pressure on the engine-abutments, and these in turn will reverse the pump-abutments. As I explained, it is desirable to drive the pump with the special form of engine shown; but obviously any motive power could be applied for this purpose. When using other power for the pump, the pump-abutments may be caused to assume their proper positions by applying to them the water-pressure from the discharge 90 of the pump the same as the steam-pressure is utilized in the engine, or, if desired, any other means may be used to yieldingly hold the abutments. Also when working the pump without connecting the abutments with those of the rotary engine the abutments should be properly packed against the walls of the offsets 18, so as to prevent the water from being forced back of the abutments, which would disturb the equilibrium of the pressure on the abutments, and therefore interfere with the effective operation of the pump. These and various other changes in the minor features of my invention may be resorted to at any time without departing 105 from the spirit thereof.

Having thus described my invention, I claim as new and desire to secure by Letters Patent—

1. A pump, comprising a pump-cylinder 110 with inlet and outlet orifices, a rotary piston, a swinging abutment mounted in the cylinder, a wall arranged at one side of the piston and turning therewith, said wall being spaced from the adjacent head of the cylinder and 115 having orifices at the respective sides of the piston, and a chamber attached to the wall and communicating with one of the openings in the wall and also communicating with the discharge or outlet orifice. 120

2. A pump, comprising a pump-cylinder with inlet and outlet orifices, a rotary piston, a swinging abutment mounted in the cylinder, a wall arranged at one side of the piston and turning therewith, said wall being spaced 125 from the adjacent head of the cylinder and having orifices at the respective sides of the piston, and a chamber attached to the wall and communicating with one of the openings in the wall and also communicating with the discharge or outlet orifice, said discharge being in the center of the cylinder and the said chamber having a centrally-disposed opening matching therewith. 130

3. A pump, comprising a cylinder with inlet and outlet orifices, a rotary piston therein, an abutment working with the piston, and walls turning with the piston and forming a 5 division between the inlet and outlet orifices, said wall having openings at opposite sides of the piston and communicating respectively with the inlet and outlet orifices.

4. A pump, comprising a pump-cylinder 10 with inlet and outlet orifices, a rotary piston, a swinging abutment mounted in the cylinder, a wall arranged at one side of the piston and turning therewith, said wall being spaced from the adjacent head of the cylinder and 15 having orifices at the respective sides of the piston, and a chamber attached to the wall and communicating with one of the openings in the wall and also communicating with the discharge or outlet orifice, the said abutment 20 being in two parts standing at an angle to

each other and pivotally mounted at their middles.

5. A pump, comprising a cylinder with inlet and outlet orifices, a rotary piston therein, an abutment working with the piston and 25 walls turning with the piston and forming a division between the inlet and outlet orifices, said wall having openings at opposite sides of the piston and communicating respectively with the inlet and outlet orifices, the said 30 abutment being in two parts standing at an angle to each other and pivotally mounted at their middle.

In testimony whereof I have signed my name to this specification in the presence of 35 two subscribing witnesses.
